UNITED STATES PATENT OFFICE.

FRED N. NELSON, OF SEATTLE, WASHINGTON, ASSIGNOR TO SAFETY BOAT CO., OF SEATTLE, WASHINGTON.

BOAT.

Application filed July 13, 1923. Serial No. 651,223.

To all whom it may concern:

Be it known that I, FRED N. NELSON, a citizen of the United States, and a resident of Seattle, King County, Washington, have invented certain new and useful Improvements in Boats, of which the following is a specification.

This invention relates to improvements in boats, particularly in launches, fishing or 10 trolling boats, and all similar types of vessels; the object of the invention being to provide non-sinkable self bailing boats, rendered so by the provision of an air tight compartment between the bottom of the boat 15 and a lower deck or a false bottom and having automatic clearing scuppers of a novel type of construction through which water entering the boat may readily drain therefrom.

20 One of the principal objects of this invention resides in the construction of the scupper and a closure therefor and in the details of construction of means whereby the closure may be locked, as occasion arises, to prevent any possible inflow of water through 25 the scupper.

Another object resides in the provision of boats of the above type equipped with water tight engine enclosures; the latter being 30 fitted with automatic ventilators which permits ready inflow of air but which close automatically to prevent any possible inlet of water that may splash or break over the boat.

35 Another object resides in the provision, in fishing or trolling boats, of a fish well, with means whereby it may be easily flushed.

Other objects reside in the various details 40 of construction and combination of parts embodied in the invention whereby a serviceable and very desirable type of construction is provided.

In accomplishing these and other objects 45 of the invention, I have provided the improved construction, the preferred forms of which are illustrated in the accompanying drawings, wherein—

Figure 1 is a longitudinal sectional view of a boat constructed in accordance with the 50 present invention.

Figure 2 is a plan view of the same.

Figure 3 is a detail view in longitudinal section, of a scupper of the preferred type of construction used in the boat.

55 Figure 4 is an enlarged plan view of a

part of the scupper, its closure and one of the closure locking devices.

Figure 5 is a side view, partly in section, illustrating the scupper closure hinge and a 60 locking device.

Figure 6 is a detail, sectional view of the valved ventilator of the engine housing.

Referring more in detail to the drawings—

1 designates, in its entirety, a boat of a 65 type embodied by the present invention. This may be of any desirable size and shape, designed to suit any specific purpose or condition, preferably it would be constructed of sheet metal but could be made of wood 70 with satisfactory results.

The boat comprises a hull 2 and a deck, or 75 false bottom 3, forming an air tight compartment 4 between the said deck and bottom of the boat. For small and intermediate sizes of vessels, this design permits placing the deck 3 above the normal water line, and the distribution of the load and weight so as to obtain the proper metacentric 80 height and seaworthiness.

Located within the boat, at a desirable 85 place, is a tank 6 wherein liquid fuel for an engine 7 is contained. Preferably, in boats of the type illustrated, the tank would be located at the stern and the engine is contained within a closed, water tight housing 8 which would be located at the most desirable place according to the character or uses to which the boat was to be put. The present drawing shows the engine located just 90 forwardly of tank 7, and the housing 8 extends partly above and partly below deck 3.

The housing cover is equipped with a 95 "goose neck" ventilator tube 10 having a downturned end with a bell shaped mouth 11 wherein a ball valve 12 is supported by a wire cage 13. This ventilator construction permits ready inlet of air into the housing but should water splash over the boat and into the ventilator spout, the ball will be automatically seated to close the mouth of the spout. The cover of the housing will be removable and provided with suitable doors to permit access to the engine.

A cabin 15 is provided in the bow of the 100 boat and rearwardly of this is a storage well 16 that extends substantially below the deck. The upper portion extends above the deck and in its covering has two hatches 17. The side walls 18 of the well extend parallel with 110

the side rail of the boat at spaced distances therefrom as shown in Figure 2, to provide aisles 19.

In order that the boat will be self bailing, I have provided a plurality of scuppers, of that character shown in Figure 3, that are located at desirable points in the deck and in such direction that the motion of the boat will accelerate an outward flow of water therethrough. Preferably there would be one at each side of the storage well and two at the stern of the boat, and they are located so as to discharge through the side walls of the hull just above the water line.

Each scupper comprises a substantially horizontal discharge tube 20 of a desirable or suitable size located below the deck 3 with its discharge end opening through the side wall or end of the hull. The opposite end is fixed to a metal ring that in turn is fastened to the under side of deck 3 in registration with a hole in the deck of the same size. This ring is of Z bar form and comprises a flange 21 that is riveted to the deck, a downwardly extending vertical portion 22 and an annular, inturned flange 23.

Located within the scupper tube and adapted to seat against the under side of the flange 23 of the ring is a closure 25 therefor of the floating valve type comprising a hollow metallic body, hingedly supported at one side by means of arms 26 fixed thereto and to a depending bracket 27 that is fixed to the flange 23; the connection between the arms and bracket consisting of a pin 28 that is fixed in the arms and is pivotally and slidably contained in a vertical slot 30 in the bracket. This closure, or valve when not locked operates automatically to permit water to drain from the boat outwardly through the scupper, but checks all inflow due to its buoyancy which causes it to be lifted and held over the opening. Should it be desired to lock the valve in closed position, tightly against the ring flange 23, this can be done by means of locking devices mounted on the flange 23. Each of these consists of a rotatable clamping member comprising a circular base or mounting flange 32 and a vertical shank 33 with a laterally turned handle 34, at its upper end. The clamps are held in position by means of flange plates 35 that are fixed to flange 23 of the ring and which overlie the base flange 32; the shanks 33 being extended through apertures 36 in the plates 35. Formed on the shanks of the locking devices are laterally extending cam flanges 37 adapted, upon rotation of the shanks by means of their handles, to engage with the under sides of holding plates 38 that are fixed to the upper side wall of the closure valve 25, and to thereby lift and tighten the closure against the ring. Gaskets 39 may be provided about the upper periphery of the clo-

sures to prevent any possible leakage when they are in closed position, and outwardly opening trap doors may be provided at the outer ends of the scupper tubes.

To provide for flushing of the fish storage well, I have provided two inlet pipes 40 and 41 which lead into the forward end of the well and through the forward side walls of the hull below the water line. These pipes are controlled by valves 43 operable from above the deck. Leading from the rear, lower corners of the well, I have provided outlet pipes 46 and 47 which discharge into the rearward scupper tubes. These are controlled by valves 48. The openings of these pipes into the well are covered by perforated plates 50 so as to prevent clogging and a free outflow of water through the pipes. When the valves of the pipes are opened, water will flow forcibly into the well through the forward pipe, if the boat is traveling forward, and will be drawn from the well through the rearward pipes by suction.

Boats of this type, and embodying all or any one of the above described features can be made in various sizes and shapes according to their particular use, and various details can be altered without departing from the spirit of the invention, and for this reason I do not wish to limit the invention only to the details herein illustrated.

Having thus described my invention, what I claim as new therein and desire to secure by Letters-Patent, is:

1. In a boat of the character described, a scupper tube disposed in the longitudinal direction of the boat, and opening at its forward end through the deck and at its rearward end through the hull, a float valve within the tube operable automatically to closed position to prevent an inflow of water, and locking means for retaining the valve closed.
2. In a boat having a deck opening, a flanged ring fixed to the deck in registration with the opening, a scupper tube leading from the said opening outwardly through the hull of the boat, a floatable closure hingedly mounted within the tube to swing between open and closed positions against the ring flange and clamping means whereby the closure may be retained in closed position.
3. In a boat comprising a deck having an opening, a scupper mounting ring fixed to the deck in registration with the opening and comprising an inturned, annular flange, a scupper tube having its inlet end mounted about and secured to said ring and its discharge end opening through the stern of the boat, a floatable closure for the scupper mounted therein, a supporting bracket fixed to the said ring and an arm fixed to the closure having a slidable and pivotal connection

with the supporting bracket whereby the float may be moved bodily from and toward the opening and clamping devices for locking the closure in closed position.

4. In a boat comprising a deck having an opening, a scupper mounting ring fixed to the deck in registration with the opening; said ring comprising an inturned annular flange, a scupper tube having its inlet end mounted about and secured to said ring and its discharge end opening through the hull of the boat, a floatable closure for the scupper tube mounted therein having support-

ing arms at one side, a supporting bracket fixed to the said ring having a vertical slot, ¹⁵ a pin extended through said arms and slot to hingedly secure the closure while permitting it to move bodily toward and from the ring, clamping devices mounted on the ring, and plates fixed on the closure to be engaged by said clamping means to hold the closure in closed position.

Signed at Seattle, King County, Washington, this 30th day of June, 1923.

FRED N. NELSON.
